UNITED STATES PATENT OFFICE.

MORELL A. WEBB, OF MARENGO, ASSIGNOR OF ONE-FOURTH TO FRANK W. BAILEY, OF CHICAGO, ILLINOIS.

BOOK-MARK.

SPECIFICATION forming part of Letters Patent No. 288,285, dated November 18, 1883.

Application filed February 27, 1883. (No model.)

To all whom it may concern:

Be it known that I, MORELL A. WEBB, a citizen of the United States, residing at Marengo, in the county of McHenry and State of Illinois, have invented a new and useful Book-Mark, of which the following is a specification, reference being had to the accompanying drawings.

This invention relates to book-marks, and to has for its object to provide a simple, inexpensive, and efficient mark that will be automatically operated by the closing of the book, and that will not mar the appearance of the latter.

15 In the drawings, Figure 1 is a perspective view of a book having my improved mark, the book being open. Fig. 2 is a sectional view of the same, taken from the top to the bottom. Fig. 3 is a transverse sectional view, 20 showing the automatic operation of the mark in dotted lines. Fig. 4 is another transverse sectional view, showing the mark in position for indicating a plurality of places at one time. Fig. 5 is a detail sectional view of the marking-strip, detached.

25 Referring to the drawings, A designates the cover of the book, which can be of any desired construction, and B designates the leaves, which can be secured to the cover in any desired manner.

30 C is a slot that is formed through all the leaves in the margin D, near where they are bound to the cover. In this slot C is arranged the mark E, which consists of a simple strip of ribbon, leather, cloth, rubber, or any other suitable material. This strip E extends entirely through the slot, and is capable of free movement therein, while the ends F F of the said strip, which project some distance from 35 the slot on each side of the series of pages of the book, are provided with shoulders G G, or other means, to obviate accidental slipping of the ends through the slot. At the same time it is desirable to have the ends of such a 40 construction that they can be readily passed through the slot to enable the marking-strip to be removed from the latter when desired.

45 The operation of this improved mark is very simple and automatic. Wherever the book

happens to be opened a small portion of the 50 strip will be exposed, as shown in Fig. 1 of the drawings, where it passes across from the slot in the page at one side to the slot in the page at the other, and the leaves can be conveniently turned in either direction without 55 interference with the marking-strip. When the book is closed, the exposed portion of the strip will automatically bend up between the pages at the place where the book was opened, instead of sliding through the slot, and the 60 loop thus automatically formed will enable the book to be opened at the exact place at which it was closed.

With this mark a number of loops can be formed in the strip, as shown in Fig. 4 of the 65 drawings, to mark a corresponding number of places, and in large books—such as ledgers, &c.—two or more marks can be used—for instance, one at the top of the book and one at the bottom. By drawing on either of the projecting ends of the strip the loops that have 70 formed between the pages or leaves can be drawn out.

I claim as my invention—

1. As an improvement in book-marks, the 75 combination, with a book having a slot passing through its leaves, of a marking-strip passed through the said slot, and having its ends projecting from the same, the said strip being arranged to slide in the said slot to form 80 loops between the pages, as set forth.

2. As an improvement in book-marks, the combination, with a book having a slot formed through its series of leaves in the margin, near 85 where the leaves are bound to the cover, of a strip passed through the said slot and arranged to slide therein, the said strip having its ends projecting from the slot, and provided with shoulders, to obviate accidental slipping of the said ends through the slot, as set forth.

90 In testimony that I claim the foregoing as my own I have hereto affixed my signature in presence of two witnesses.

MORELL ALONZO WEBB.
